CONDIMENT FUNNEL SET

Ethlyn B. Gaylord, Temple City, Calif.

Application August 12, 1952, Serial No. 20,975

Term of patent 7 years

(Cl. D44—29)

To all whom it may concern:

Be it known that I, Ethlyn B. Gaylord, a citizen of the United States and a resident of Temple City, California, have invented a new, original, and ornamental Design for Condiment Funnel Set, of which the following is a specification; reference being had to the accompanying drawing, which forms a part of said specification and in which drawing:

Fig. 1 is a front elevation of a condiment funnel set, embodying my new design,

Fig. 2 is a rear elevation of the condiment funnel set shown in Fig. 1, and

Fig. 3 is a side elevation as viewed from the right hand side of Fig. 1.

Portions of Fig. 1 are stippled to indicate contrasting color areas. The dominant feature of my design resides in those portions shown in full lines.

I claim:

The ornamental design for a condiment funnel set, substantially as shown and described.

ETHLYN B. GAYLORD.
